UNITED STATES PATENT OFFICE.

CHARLES LOUIS LEVEQUE, OF DETROIT, MICHIGAN.

CARBURETOR.

Application filed July 30, 1926. Serial No. 125,842.

My invention relates to improvements in carburetors.

The object is to provide a carburetor of simple construction adapted to efficiently operate to provide the combustion chamber with which it is associated with the required amount of fuel mixture properly proportioned to serve in the most satisfactory manner at all times the needs of the engine.

10 An additional object is to provide such a carburetor so constructed and arranged that fuel is fed to a normally closed fuel nozzle within the mixing chamber thereof, the outlet from which fuel nozzle is regulated by a valve from which the fuel is discharged into the mixing chamber through a restricted passageway encircling a portion of said valve, which passageway is normally opened to the suction within the mixing chamber.

20 A meritorious feature of my invention is the provision of a carburetor such as is herein described wherein a nozzle well carrying a control valve is disposed within the mixing chamber and is so supported by a removable portion of the wall of the mixing chamber as to be capable of ready removal therewith for inspection or cleaning.

An additional object of merit is the provision in a carburetor of the character described provided with a fuel nozzle as hereinabove set forth with a mixing chamber provided with an air inlet and a fuel mixture outlet controlled by a barrel throttle, the movement of which is coordinated with the movement of the fuel valve controlling the outlet of the fuel nozzle.

My improved carburetor is of such a character that the float chamber ordinarily provided in carburetor construction is dispensed with and the fuel inlet to the mixing chamber leads directly from the provided source of fuel supply to the fuel nozzle disposed within the mixing chamber and the control fuel. The admission of air to the mixing chamber, and the discharge of the fuel mixture from the mixing chamber is regulated manually by operator.

Other meritorious features of my carburetor construction and advantages thereof will more fully appear from the following specification descriptive of the illustrative

embodiment shown in the accompanying drawings and defined in the appended claim.

In the drawings:

Fig. 1 is a plan of my improved carburetor.

Fig. 2 is a vertical sectional view taken on line 2—2 of Fig. 1.

Fig. 3 is a cross-sectional view taken on line 3—3 of Fig. 2.

Fig. 4 is a cross-sectional view taken on line 4—4 of Fig. 2.

Fig. 5 is a perspective of a portion of the operating mechanism.

Fig. 6 is a perspective of the barrel throttle.

My improved carburetor is adapted to be used in connection with internal combustion engines such as are commonly employed in automobile construction and is connected up in the usual manner with the combustion chambers and with a suitable source of fuel supply, which auxiliary connections are not shown in the drawings as they form no part of my invention.

My invention relates to the improved carburetor design. In the drawing, 10 indicates a mixing chamber having a fuel mixture outlet 12 and an air inlet 14. This mixing chamber has a screw cap 16 at one end which is cut away as at 18, which openings 18 are controlled by an adjustable screw plate 20 having a knurled periphery and carrying a locking device 22 which engages in a similarly knurled periphery formed on the cap 16 to hold the plate at adjusted positions with respect to said cap to regulate the openings 18 through the cap.

The mixing chamber has a removable wall plate 24 held thereon in a suitable manner and it is here shown as secured in place by screws 26, which wall portion carries a fuel nozzle 28 that has a fuel inlet 30 leading to a conduit 32 which extends to a suitable source of fuel supply now shown in the drawings. This fuel nozzle is tubular in shape and is provided with an end closure 34 at one end and a cap 36 at the opposite end, which cap has a discharge outlet 38. A valve 40 is located within the nozzle. This valve has a beveled portion 42 adapted to

seat against a similarly beveled portion 44 at the mouth of the opening 38 through the cap 36. The valve is reduced in diameter intermediate its ends and opposite the fuel inlet 30. It has a bearing at the lower end within the nozzle 28 and a projection at such end encircled by a spring 46 which holds the valve upwardly normally closed. The upper end of the valve is provided with a stem 48 which extends through the opening 38 into the interior of the mixing chamber above the cap 36. This stem is of such a size that it is spaced from the wall of the outlet of the cap a limited distance providing a restricted fuel discharge passageway through said cap about said stem, which passageway is open to the suction in the mixing chamber.

A barrel throttle indicated in assembly 20 as 50 in Fig. 6 is disposed within the mixing chamber as shown in Fig. 2. This barrel throttle is provided with an aperture 52 adapted to register with the fuel mixture outlet 12 from the mixing chamber and with 25 an aperture 54 adapted to register with the air intake 14 into the mixing chamber and with a slotted portion 56 adapted to permit rotatable movement of the barrel with respect to the conduit 30 leading to the fuel 30 nozzle 28.

The barrel throttle is adapted to be rotated to regulate the air inlet opening in the mixing chamber and the fuel discharge opening therefrom and an operating connection is 35 provided to actuate said barrel throttle. This operating connection also serves to open the valve 40 within the fuel nozzle. The operating connection above referred to is extended to a suitable point to be conveniently 40 controlled by the operator. The mixing chamber is provided at the upper end with an extension 56. Within this extension is fixed a tubular bearing 58. Rotatably supported within this tubular bearing is a portion 60. This portion 60 carries a yoke 62 from which projects an arm 64 adapted to be coupled with a suitable, manually operable connection not shown. The swinging of the arm in one direction or the other 45 swings the yoke and rotates the portion 60. A spindle 66 is threaded into the portion 60. This spindle terminates at the upper end in a head 68 adapted to be engaged to actuate the spindle. An indicator 70 is carried by 50 the spindle. The arm 64 is provided with an arcuate face portion 72 graduated to register the movement of the indicator 70. The spindle 66 extends through the tubular portion 60 into the barrel throttle 50 and into 55 engagement with the end of the valve stem 48.

The end of the barrel throttle is cut away at 74 and the spindle 66 is provided with an integral plate portion 76, receivable within the opening 74 so that upon rotation of

the spindle 66 the barrel throttle will be likewise rotated while the spindle 66 may move axially with respect to said barrel throttle, the plate 76 being slidably longitudinally relative to the opening 76 in the end of the 76 barrel throttle.

When the arm 64 is swung to either the right or the left, the portion 60 rotates within the bearing 58 and carries with it the spindle 66 and a barrel throttle is rotated to open or close the openings 12 and 14 into the mixing chamber. Bearing 58 is provided on its lower face with a cam surface 78, terminating in a shoulder 80. This cam surface engages the plate 76 as there is provided an expansion spring 82 shown in Fig. 2. As the plate 76 is rigidly secured to the spindle 66 and is held by the spring 82 against the cam face 78 of the bearing 58, rotation of the spindle will serve to actuate the same axially, thereby actuating the valve member 40. It will therefore appear that rotation of the spindle will rotate the barrel throttle to regulate the openings controlled thereby and will also actuate the fuel valve within the fuel nozzle to regulate the opening controlled thereby, yet the spindle 66 may be adjusted by engagement of the head 68 axially to adjust the permitted opening of the valve 40 without varying the position of the barrel throttle 50. It will therefore appear that the air inlet opening to the mixing chamber, the fuel mixture outlet therefrom, and the fuel nozzle valve within the nozzle are cojointly regulated through the swinging of the arm 64 to open and close said valved openings in any direction proportioned to each other and that the fuel valve opening may be adjusted independently of the operation of the barrel throttle. 105

Upon the opening of the valves to admit fuel mixture to the combustion chamber a film of fuel is drawn through the annular passageway in the outlet 38 about the valve stem 48 into the mixing chamber where it mixes with the air entering the same and the mixture is carried through the outlet 12. The vaporization of the fuel is unusually efficient. The entire device is subject to a single control. The fuel nozzle being supported by the removable wall plate 24 is readily removable from the mixing chamber for inspection or cleaning. 110

A stop, in the form of a screw member 84, is provided. This stop 84 is threaded through the wall of the casing 10 and projects into a slot 86 formed in the barrel 50 which limits the rotation of the barrel and prevents the same from dropping out of the casing upon removal of the end plate 16. 115

What I claim is:

In a carburetor, a mixing chamber having a fuel mixture outlet opening and an air inlet opening, a barrel throttle rotatably mounted within said mixing chamber con-

trolling said openings, a fuel nozzle in said chamber, a valve mounted within said nozzle and held yieldingly upwardly by a spring to close the outlet of the nozzle, said valve provided with a stem extending upwardly through the nozzle outlet into the interior of the mixing chamber, a rotatably operable axially movable member extending through the top of the barrel throttle into engagement with the end of said valve stem, said barrel throttle coupled with a part on the operating member to rotate with said member while permitting relative axial movement of the operating member therethrough, a spring tending to hold said operating member upwardly away from said valve stem, a part having a stationary cam face disposed above said barrel throttle, a part on said operating member cooperating with said operating cam face whereby upon rotation of said member relative to said cam face, the operating member is moved axially against the resistance of said spring to depress the valve stem and the valve.

In testimony whereof, I sign this specification.

CHARLES LOUIS LEVEQUE.
